UNITED STATES PATENT OFFICE.

WILLIAM B. GLISSON, OF RUTHERFORD, TENNESSEE.

MUSICAL NOTATION.

Application filed September 27, 1924. Serial No. 740,231.

To all whom it may concern:

Be it known that I, WILLIAM B. GLISSON, a citizen of the United States, residing at Rutherford, in the county of Gibson and 5 State of Tennessee, have invented certain new and useful Improvements in Musical Notation, of which the following is a specification.

The invention relates to an improved system of musical notation, in which time, clefs, and other elements of the notation are represented by numerals or by initials, so that the scale can be printed without any extra symbols. The object of the invention is to 10 simplify musical notation both from the point of view of the printer and of the student.

The system is diagrammatically illustrated in the accompanying drawing, in 15 which:—

Fig. 1 is a representation of the diatonic scale;

Fig. 2 is a representation of the chromatic scale ascending;

25 Fig. 3 shows the chromatic scale descending;

Fig. 4 indicates the mode of representing time for vocal music;

30 Fig. 5 indicates a mode of representing time for instrumental music;

Figs. 6, 7, 8, 9 and 10 are views similar to Figs. 1, 2, 3, 4 and 5 respectively, but for a different clef.

Fig. 11 shows the manner of representing 35 diatonic tones.

Fig. 12 shows the manner of representing chromatic tones, ascending and descending;

40 Fig. 13 shows the manner of representing the different clefs;

Fig. 14 indicates the manner of representing tone lengths and rests.

Referring first to Figs. 1 to 10 inclusive, it will be noted that the improved scale 45 requires but two primary lines for each clef, these lines being represented by the numerals 20 and 21. The tones do, re, mi, fa, sol, la, ti and do are represented by the respective initials of these tones as indicated in 50 Fig. 11, instead of by symbols located upon a particular line of the scale, as in the usual notation. I preferably locate low do on the lowest line 20 of the scale, and re, mi, fa between the lines 20 and 21. The tones sol,

la, ti, are preferably located above the line 55 21 while, high do, if it be employed in the scale, will be located upon a supplementary line 22, above the line 21. If it is necessary to go up an octave in the scale, the additional notes may be located above the line 60 22, as indicated in Figs. 5 and 10.

As shown in Figs. 1, 6 and 13, the clefs, instead of being represented by special symbols are designated merely by capital letters, G, C and F. The key in which the scale is 65 written is indicated by a larger numeral, as shown in Figs. 1 and 6. The time is likewise represented by numerals, these numerals being smaller than those representing the key.

Tone lengths, as shown in Figs. 4, 5, 9, 70 10 and 14, are indicated by numerals, which are located in a line vertically above or below the particular notes whose time they represent. Dotted notes are indicated by 75 a period after the numeral which is to be prolonged. Rests, as shown in Figs. 4, 9 and 14, are likewise indicated by numerals, but these numerals are preferably written horizontally instead of upright as are the 80 time numerals.

The chromatic tones as indicated in Figs. 2, 3, 7, 8 and 14 are indicated by the initials of the tone, but are written horizontally instead of upright, in order to distinguish 85 them from the diatonic tones. In the chromatic scale ascending the initials are tilted 90° in a clockwise direction, whereas in the descending scale the chromatic tones are tilted 90° in a counterclockwise direction.

90 It will be readily seen that according to the improved system of notation all the terms necessary to writing music can be designated by letters or numerals which may be printed by the ordinary type with which every printing press is equipped. It will be further seen that all the notes for a single octave, with the exception of do, may be printed upon not more than two horizontal lines. If desired these notes may be printed upon single line, but it is generally preferable to use two lines for this purpose. By this reduction in the number of lines a saving in printing is effected and greater simplicity is obtained.

105 It has been found in practice that the improved scale is much more readily mastered by the student, than the standard scale, and

can be learned by any one having a rudimentary knowledge of fractions.

Obviously the invention is subject to modifications such as fall within the scope of the 5 appended claims:—

1. A music sheet in which time is represented by numerals in the upright position and rests by numerals tilted from the upright position.
- 10 2. A music sheet in which notes are represented by letters and tone lengths by numerals, the letters designating a plurality of different notes of a single octave being arranged in horizontal alignment, the numeral corresponding to each letter being in
- 15

vertical alignment with said letter, and all the numerals being in horizontal alignment with each other.

3. A music sheet as defined in claim 2, in which the letters representing re, mi, and fa or the corresponding diatonic tones, are arranged in horizontal alignment and the letters representing sol, la, ti, and the corresponding diatonic tones are likewise arranged in horizontal alignment, but above 20 the first series of letters.

In testimony whereof I affix my signature.

WILLIAM B. GLISSON.
